United States Patent Office

Des. 188,012
Patented May 24, 1960

188,012

SEWING MACHINE

Phillip S. Morse, 193 Wyndcliff Road, Scarsdale, N.Y.

Filed Nov. 10, 1959, Ser. No. 58,293

Term of patent 14 years

(Cl. D70—1)

FIG.1

FIG.2

FIG.3

FIG.4

FIG.5

Fig. 1 is a front perspective view of a sewing machine, showing my new design;

Fig. 2 is a rear perspective view thereof;

Fig. 3 is a top view thereof;

Fig. 4 is an end perspective view taken from the left end of Fig. 1; and

Fig. 5 is an end perspective view taken from the right end of Fig. 1.

I claim:

The ornamental design for a sewing machine, substantially as shown.
